Primary Examiner — Sheryl Lane*Assistant Examiner* — Calvin E Vansant(74) *Attorney, Agent, or Firm* — Culpepper IP, LLLC;
Kerry S. Culpepper(57) **CLAIM**

I claim the ornamental design for a wash bowl, as shown.

DESCRIPTION

FIG. 1 is a front view;

FIG. 2 is a rear view;

FIG. 3 is a right side view;

FIG. 4 is a left side view;

FIG. 5 is a top plan view;

FIG. 6 is a bottom plan view;

FIG. 7 is a cross-sectional view along lines A-A of FIG. 3; and,

FIG. 8 a perspective view.

Any broken lines shown represent unclaimed subject matter and form no part of the claimed design. Additionally, the unevenly broken lines in the drawings define the boundaries of the claimed design.
